(57) **CLAIM**

The ornamental design for a solar wall light, as shown and described.

DESCRIPTION

FIG. 1 is a front perspective view of the embodiment 1, showing my new design;

FIG. 2 is a rear perspective view thereof of the embodiment 1;

FIG. 3 is a front view thereof of the embodiment 1;

FIG. 4 is a rear view thereof of the embodiment 1;

FIG. 5 is a left side view thereof of the embodiment 1;

FIG. 6 is a right side view thereof of the embodiment 1;

FIG. 7 is a top view thereof of the embodiment 1;

FIG. 8 is a bottom view thereof of the embodiment 1;

FIG. 9 is a front perspective view thereof of the embodiment 2;

FIG. 10 is a rear perspective view thereof of the embodiment 2;

FIG. 11 is a front view thereof of the embodiment 2;

FIG. 12 is a rear view thereof of the embodiment 2;

FIG. 13 is a left side view thereof of the embodiment 2;

FIG. 14 is a right side view thereof of the embodiment 2;

FIG. 15 is a top view thereof of the embodiment 2;

FIG. 16 is a bottom view thereof of the embodiment 2;

FIG. 17 is a front perspective view thereof of the embodiment 3;

FIG. 18 is a rear perspective view thereof of the embodiment 3;

FIG. 19 is a front view thereof of the embodiment 3;

FIG. 20 is a rear view thereof of the embodiment 3;

FIG. 21 is a left side view thereof of the embodiment 3;

FIG. 22 is a right side view thereof of the embodiment 3;

FIG. 23 is a top view thereof of the embodiment 3;

FIG. 24 is a bottom view thereof of the embodiment 3;

FIG. 25 is a front perspective view thereof of the embodiment 4;

FIG. 26 is a rear perspective view thereof of the embodiment 4;

FIG. 27 is a front view thereof of the embodiment 4;

FIG. 28 is a rear view thereof of the embodiment 4;

FIG. 29 is a left side view thereof of the embodiment 4;

FIG. 30 is a right side view thereof of the embodiment 4;

(Continued)

FIG. 31 is a top view thereof of the embodiment 4; and, FIG. 32 is a bottom view thereof of the embodiment 4. The broken lines in the drawings illustrate the portions of the solar wall light, which form no part of the claimed design.
